CLAIM

The ornamental design for a chin guard for a face shield, as shown and described.

DESCRIPTION

FIG. 1 is a front perspective view of a chin guard for a face shield showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is a front perspective view of a chin guard for a face shield showing the chin guard attached to a face shield, to illustrate a typical environment in which the chin guard would be used;

FIG. 10 is a rear perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

In the drawings, the broken lines illustrate environmental features that form no part of the claimed design.
